UNITED STATES PATENT OFFICE.

ROBERT N. LE CRON, OF ST. LOUIS, MISSOURI.

PRESSURE CASTING APPARATUS.

No. 927,661.

Specification of Letters Patent.

Patented July 13, 1909.

Application filed April 20, 1908. Serial No. 428,175.

To all whom it may concern:

Be it known that I, ROBERT N. LE CRON, a citizen of the United States, residing at St. Louis, in the State of Missouri, have invented certain new and useful Improvements in Pressure Casting Apparatus; and I do hereby declare the following to be a full, clear, and exact description of the same, reference being had to the accompanying drawings, forming a part of this specification, and to the figures and letters of reference marked thereon.

This invention relates to improvements in apparatus for facilitating the making of small and delicate castings with the aid of pneumatic or gas pressure for forcing the molten metal into the interstices of the mold.

The apparatus forming the subject-matter of the present application is particularly designed for use by dentists in the making of inlay castings or cast metal dental appliances of any character, although it is well adapted for use by jewelers, and others, for the production or reproduction of articles of jewelry for personal wear or adornment.

The objects of the invention are to provide a simple, inexpensive apparatus not liable to get out of order or be broken in use.

A further object of the invention is to provide an apparatus which shall be as nearly as possible automatic in the application of the pressure to the molten metal, and which requires no complicated accessories for its operation.

A further object of the invention is to provide an apparatus with which flasks or cups for molds of various sizes may be employed, thereby enabling the user to make small and delicate castings without the necessity of employing a flask of large dimensions, thereby effecting a saving in investment material, and other expenses incident to the employment of flasks of larger dimensions than necessary for the particular object being cast.

Further objects of the invention are to provide a receiver or casting chamber adapted to be closed or made air-tight without the employment of packings and to provide for the admission of air or gas pressure to the receiver without danger of chilling the molten metal.

The invention consists in certain novel details of construction and combinations and arrangements of parts all as will be now de-

scribed and particularly pointed out in the appended claims.

Referring to the accompanying drawings: Figure 1 is a perspective view of an apparatus embodying the present improvements, portions being broken away, and the pressure supply tank shown diagrammatically. Fig. 2 is a vertical section taken in a plane from front to rear of the casting apparatus proper. Fig. 3 is a sectional view of flasks to illustrate the fact that flasks of various dimensions may be employed in the same apparatus. Fig. 4 is a sectional view showing an inverted cup containing a material, the use of which will be hereinafter explained.

Like characters of reference in the several figures indicate the same parts.

The casting apparatus proper embodies a receiver which is of proper dimensions to contain a flask of the largest dimensions capable of use with the apparatus, and, as shown, this receiver is formed by a bottom section A and a top section B, one of said sections being movable toward and from the other to close and open the receiver, the meeting edges being preferably mitered or made to telescope, one within the other, as at a, b, in order to form a receiver which is substantially closed against the escape of internal pressure before the two sections have completed their closing movement. In the preferred construction, the lower section A is provided with an extended base A¹, adapted to be mounted on a table or other suitable support, and extending upwardly from this base A¹ are guide rods C, upon which the upper section B is mounted and guided in its movement. As a convenient and thoroughly mechanical construction, the guides C may be connected by a bridge-piece C¹, in which a central stem B¹ projecting upwardly from the upper section B takes its bearing. The stem B¹ is conveniently provided with a handle B² at the upper end, whereby the upper section B of the receiver may be moved by the operator into either its open or closed position, although in the preferred construction, and as shown, the upper section B is provided with downwardly extending rod and chain connections such as indicated at D, D¹, adapted to support a cross piece forming a foot or treadle connection D², whereby the upper section may be drawn down with any necessary or desired

- pressure, and without undue exertion on the part of the operator. The upper or movable section is adapted to be held in its closed position and where desired in its open position by a spring-pressed catch E, preferably pivotally mounted on the bridge-piece C¹ and adapted to enter one or the other of the notches e in the stem B¹ of the movable section.
- 10 Air or gas pressure is admitted to the receiver through a supply duct G, Fig. 2, to which the pressure may be conducted through a flexible tube H, from a pressure supply tank H¹, or other suitable source, and the admission of the pressure to the receiver is controlled by a valve adapted to be opened by the closing movement of the receiver after the receiver has been sufficiently closed to prevent the escape of internal pressure between the meeting edges of the sections.

The valve for controlling the pressure supply, lettered I in the accompanying drawings, is conveniently located in a valve casing K, forming a part of the pressure supply duct and mounted directly upon the upper or movable section B of the receiver. An operating or opening stem i for the valve extends downwardly below the valve casing 30 in position to contact with an adjustable stop L, mounted on or forming a part of the lower section A, the arrangement being such that the stop may be adjusted to open the valve only after the two sections have 35 commenced to telescope together and the final opening of the valve will be effected when the closing movement of the receiver is completed.

The bottom of the lower section is provided with a central vent A² and the inner 40 face of said bottom is preferably made substantially flat and smooth, while the cups or flasks M are provided with downwardly extending peripheral flanges m adapted to seat 45 on said bottom around the vent A² and to form with said bottom a substantial seal against the escape of pressure beneath the flange. The bottom of the flasks is perforated and elevated slightly above the edges 50 of the flanges, thereby providing an air chamber within said flanges, and as a consequence when the receiver is closed and pressure admitted thereto above and around the flask, the only escape for said pressure is 55 through the flask itself. By having the bottom of the flask uniformly perforated the pressure is equally distributed and, as will hereinafter appear, each part of a mold may be effectually relieved from its contained air by the escape of the latter through 60 the interstices of the investing material, without danger of forming channels of sufficient size to permit the entry of molten metal.

In using the apparatus, the flask is prepared usually by surrounding the wax pat-

tern with investing material and embedding the said pattern in such material within the flask, a suitable depression or cavity being formed in the upper surface of the investing material in which the metal may be melted by means of a blow-pipe, electric arc, or usual appliances employed for this purpose. The wax pattern having been removed, preferably by inverting the flask and heating the same, the flask is placed in the lower section of the receiver and the metal placed in the depression in the top of the flask and melted. As soon as the metal is sufficiently molten the receiver is closed and the pressure simultaneously admitted, thereby forcing the molten metal into the mold, and at the same time forcing the air which may have occupied the area of the mold to a greater or less extent out through the investing material, perforated bottom of the flask, and vent A².

In order to make the use of the apparatus possible where no auxiliary pressure supply is available, the adjustable stop L may be moved, so that the valve will not be opened, or the pressure supply duct may be plugged in any suitable way, and to create a pressure when the receiver is closed, steam may be generated by the heat of the flask and adjacent parts from the water contained in a pad of asbestos or other material located in the upper movable section B. For instance, the inverted cup or box N, Fig. 4, may be located in the upper section B and contain either an absorbent pad of asbestos or a plastic molding material, indicated at N¹. If the material employed is a plastic mass, the cup N should be of such dimensions as to pass down around the upper edge of the flask, thereby bringing the plastic mass into contact with the upper surface of the investing material and flask. As the result of this operation, the air trapped in the cavity in the flask, or the plastic material itself coming into contact with the molten metal will force the latter down into the mold, the operation in all cases resulting in the air being forced out of the mold as the molten metal enters the same, thereby insuring a perfect reproduction of the mold cavity, without blow holes or fins of any character, save the usual sprues formed by the entrance openings for the metal.

It will be noted that the sections of the receiver are closed substantially air tight without the use of packings of any description, thereby eliminating the danger of rendering the apparatus inoperative by burning or drying out of the packings. The only escape for the air is through the special investing material, and the flasks do not have to be carefully centered or fitted into place so long as the central vent is under the perforated bottom and with apparatus of ordinary size the flasks are all of such size that even when in contact with the side of

the receiver the vent will be within the annular flange. When the flasks are in place and the upper section of the receiver elevated, the top of the flasks are left entirely open 5 and free for the use of a flux and for the application of the heating flame from a blow pipe or heater manipulated in the hand of the operator. It will also be noted that the air or gas is admitted to the receiver trans- 10 versely or at the side, thus avoiding danger of chilling the molten metal.

Having thus described the invention, what is claimed, is:

1. In a pressure casting apparatus, the combination with the receiver for the flask formed in separable sections movable one toward and from the other and the lower section being provided with a bottom vent, of a flask having a perforated bottom and a per- 20 ipheral flange around the perforated bottom adapted to seat in the lower section around the said vent, whereby air and gases may be forced from the receiver through the flask.
- 25 2. In a pressure casting apparatus, the combination with the receiver for the flask formed in separable sections movable one toward and from the other, and the lower section being provided with a plane internal 30 face having a vent therein, of a flask having a perforated bottom and a downwardly extending peripheral flange adapted to seat on the plane face of the receiver around the vent.
- 35 3. In a pressure casting apparatus, the combination with the receiver for the flask formed in separable upper and lower sections, of rods mounted on the lower section and forming the guide ways for the upper 40 section and a catch for holding the sections closed.

4. In a pressure casting apparatus, the combination with the receiver for the flask formed in separable upper and lower sec- 45 tions, the lower section being provided with a vented bottom having a plane inner face, of guide rods for the upper section mounted on the lower section, a catch for holding the sections closed, and a flask having a per- 50forated bottom and peripheral flange seating around the said vent.

5. In a pressure casting apparatus, the combination with the receiver for the flask formed in separable upper and lower sec- 55 tions, the lower section being provided with a vented bottom, of guide rods for the upper section supported by the lower section, down-

wardly extending connections for depressing the upper section, and a catch for holding the upper section down.

6. In a pressure casting apparatus, the combination with the receiver for the flask embodying the bottom section having an extended base and vented bottom and the vertical guides supported by said section, of 60 the inverted cup-shaped top section mounted on the vertical guides and movable toward and from the bottom section, a downwardly extending foot operated connection for depressing the upper section, and a spring 70 pressed catch for holding the upper section against movement.

7. In a pressure casting apparatus, the combination with the receiver for the flask embodying upper and lower sections mov- 75 able one toward and from the other to close and open the receiver, the lower section being provided with a vented bottom, of an air duct for supplying pressure to the receiver, a valve in said duct opened by the 80 movement of the sections to close the receiver, and a flask having a perforated bottom adapted to seat over said vent, whereby air and gases in the flask may escape through the perforated bottom and vent.

8. In a pressure casting apparatus, the combination with the receiver for the flask embodying upper and lower sections mov- 90 able one toward and from the other to close and open the receiver and the lower section being provided with a vented bottom, of an air duct for supplying pressure to the receiver and a control valve for said duct mounted on one section and having a stem projecting in position to contact with the 95 other section to open the valve as the receiver is closed.

9. In a pressure casting apparatus, the combination with the receiver for the flask embodying upper and lower sections mov- 100 able one toward and from the other to close and open the receiver and the lower section being provided with a vented bottom, of a pressure inlet duct carried by the upper section, and a valve controlling said duct 105 having a downwardly extending operating stem adapted to contact with the lower section to open the valve as the sections come together.
